ABSTRACT

A ceiling table for a partial formwork of a concrete ceiling. The ceiling table has at least one formwork element, in particular multiple formwork elements, which can be assembled on a lower frame of the ceiling table in a nondestructive manner and which can be disassembled from the lower frame. The ceiling table has a support skeleton on which at least one formwork element, in particular multiple formwork elements, is/are arranged. The support skeleton can have multiple braces which can be connected together and separated from one another in a nondestructive manner. The support skeleton preferably has a pair of main supports, in particular parallel running main supports, on which a pair of edge supports and at least one central support that is arranged between the edge supports are arranged. The edge supports and the central support run preferably parallel to one another.

**CEILING TABLE AND CEILING
FORMWORK COMPRISING SUCH A
CEILING TABLE**

FIELD OF THE INVENTION

The invention relates to a ceiling table for a ceiling formwork, the ceiling table having a lower frame comprising multiple supports. The invention further relates to a ceiling formwork comprising such a ceiling table.

BACKGROUND OF THE INVENTION

The use of formwork elements to build concrete ceilings is known. In particular, frame panel formwork elements are used that at least partially form a mold to be filled with liquid concrete. Once the concrete has hardened, the formwork elements are removed.

Using the formwork elements, ceilings can be designed flexibly because the ceiling formwork is assembled from many individual formwork elements. To pour concrete quickly for large-area ceilings, it has been proven useful to use ceiling tables that have a lower frame and a large formwork surface. Such ceiling tables are brought to the next floor using a transportation fork once the freshly poured concrete ceiling has hardened. The disadvantage of the known ceiling tables is that they are cumbersome to transport and can only be used in an inflexible manner. Furthermore, the known ceiling tables are often incompatible with other formwork elements.

SUMMARY OF THE INVENTION

The object of the present invention is therefore to create a ceiling table that makes it possible to quickly create a ceiling framework with maximum flexibility. The object of the invention is also to provide a ceiling formwork comprising such a ceiling table.

This object is achieved according to the invention by a ceiling table of a ceiling formwork, the ceiling table having a lower frame comprising multiple supports, characterized in that the ceiling table has a support skeleton that is attached to the lower frame, the ceiling table having multiple formwork elements, the formwork elements each having a formwork element frame and a formwork shell arranged on the formwork element frame, at least one formwork element being attached to the support skeleton in a reversibly detachable manner and by a ceiling framework comprising a ceiling table, a support head and a further formwork element, the support head being arranged on the further formwork element in a reversibly detachable manner and arranged on the ceiling table in a reversibly detachable manner. The dependent claims specify useful further developments.

The object according to the invention is thus achieved by a ceiling table comprising a lower frame having multiple supports. The ceiling table has a support skeleton. The support skeleton is arranged or formed on the lower frame. Formwork elements are mounted to the support skeleton. The formwork elements have a formwork element frame. A formwork shell of the formwork element is arranged on the formwork element frame. At least one formwork element is mounted to the support skeleton in a reversibly detachable manner.

The ceiling table can be flexibly adapted to a building structure via the at least one formwork element that is mounted in a reversibly detachable manner. For example,

2

the at least one formwork element that is mounted in a reversibly detachable manner can be removed from the ceiling table to create a cavity for a concrete column. Because of the at least partial disassembly capability of the ceiling table, the ceiling table can furthermore be transported in a compact manner with a truck.

According to the invention, a ceiling table of a ceiling formwork is in particular a (preferably rigid) unit for creating a ceiling formwork that makes uniform implementation together with the supports of the ceiling table and the formwork elements of the ceiling table possible.

The flexibility of the ceiling table is further increased if multiple formwork elements, in particular all formwork elements, of the ceiling table are mounted to the support skeleton in a reversibly detachable manner.

Alternatively or in addition to this, the lower frame can be arranged on the support skeleton in a reversibly detachable manner.

20 The support skeleton can have a first main support and a first edge support that is mounted to the first main support in a reversibly detachable manner. The support skeleton can be designed particularly flexibly as a result.

25 The at least one formwork element is preferably rectangular. Furthermore, multiple formwork elements, in particular all formwork elements, are preferably rectangular.

The formwork elements can be identical in design to make the construction of the ceiling table easier.

30 To easily arrange the at least one formwork element that is mounted to the support skeleton in a reversibly detachable manner and to be able to remove it from the support skeleton, the longitudinal axis of the first main support preferably runs perpendicularly offset relative to the longitudinal axis of the first edge support.

35 The support skeleton can have a second edge support that is mounted to the first main support in a reversibly detachable manner. The longitudinal axis of the second edge support preferably runs parallel to the longitudinal axis of the first edge support.

40 In a further preferred embodiment of the invention, the support skeleton has a second main support. The longitudinal axis of the second main support can run parallel to the first main support. The second main support can be mounted to the first edge support in a reversibly detachable manner. Alternatively or in addition to this, the second main support can be arranged on the second edge support in a reversibly detachable manner.

45 To arrange multiple formwork elements on the support skeleton, the support skeleton can have at least one central support that is arranged on the first main support in a reversibly detachable manner. The longitudinal axis of the central support can run parallel to the longitudinal axis of the first edge support and/or parallel to the longitudinal axis of the second edge support.

50 In a further embodiment of the ceiling table, the lower frame can have multiple rolls such that the ceiling table can easily be displaced.

55 At least one formwork element, preferably multiple formwork elements, in particular all formwork elements, can each have a coupling point, in particular in the form of at least one locking projection, to arrange a support head of the ceiling formwork. As a result of this, the formwork surface of the ceiling table can be expanded in a particularly flexible manner with further formwork elements.

60 Alternatively or in addition to this, at least one formwork element can have at least one plastic corner. As a result of

this, damaged corners that are especially at risk on formwork elements can be repaired easily by replacing the plastic corner.

The object according to the invention is further achieved by a ceiling formwork comprising a previously described ceiling table, a support head and a further formwork element. The support head can be arranged to the further formwork element in a reversibly detachable manner as well as arranged on the ceiling table in a reversibly detachable manner. The ceiling formwork thus comprises a ceiling table that was expanded by a further formwork element.

The ceiling formwork can have a ceiling support comprising the support head and a formwork support such that the further formwork element can be supported on the substrate not only via the ceiling table, but also via the ceiling support.

Further features and advantages of the invention are presented in the following description of multiple exemplary embodiments of the invention, in the claims and in the figures of the drawing that shows details that are essential to the invention.

The features shown in the drawing are depicted in such a way that the special features according to the invention can be made clearly visible. The various features can each be realized in variants of the invention individually or in groups in any combination.

BRIEF DESCRIPTION OF THE DRAWINGS

Shown are:

FIG. 1 is a perspective view of a ceiling table comprising multiple formwork elements and a lower frame;

FIG. 2 is a perspective view of a main support of the ceiling table according to FIG. 1;

FIG. 3 is a perspective view of an edge support of the ceiling table according to FIG. 1;

FIG. 4 is a perspective view of a support skeleton of a ceiling table comprising two main supports and two edge supports;

FIG. 5 is a perspective view of a central support;

FIG. 6 is a perspective view of a support skeleton comprising multiple central supports;

FIG. 7 is a perspective view of a formwork element;

FIG. 8 is a perspective view of the support skeleton from FIG. 6 comprising multiple formwork elements according to FIG. 7;

FIG. 9 is a perspective view of a support skeleton fully provided with formwork elements;

FIG. 10 is a perspective view of a ceiling formwork comprising a ceiling table and further formwork elements arranged thereon;

FIG. 11 is a top view of a formwork element or formwork shell, support heads being coupled to the formwork element;

FIG. 12 is a perspective view of a ceiling table comprising a removed formwork element; and

FIG. 13 is a perspective view of two ceiling tables according to FIG. 12.

DETAILED DESCRIPTION

FIG. 1 shows a ceiling table 10 comprising multiple formwork elements of which only formwork elements 12a-c are provided with a reference character for the sake of clarity. Formwork elements 12a-c are arranged on a support skeleton 14 of ceiling table 10 in such a way that they can be removed without being destroyed. Support skeleton 14 is arranged on a lower frame 16 comprising multiple supports

of which only supports 18a-c are provided with a reference character for the sake of clarity. Support skeleton 14 is arranged on lower frame 16 in a reversibly detachable manner. Individual parts of support skeleton 14 are explained below.

FIG. 2 shows a first main support 20a of support skeleton 14 (see FIG. 1) comprising attachment points 22a-c for lower frame 16 (see FIG. 1).

FIG. 3 shows a first edge support 24a of support skeleton 14 (see FIG. 1). First edge support 24a has attachment points 22d, 22e for mounting first edge support 24a to first main support 20a in a reversibly detachable manner (see FIGS. 2 and 4).

FIG. 4 shows a support skeleton 14 comprising a first edge support 24a and a second edge support 24b. Edge supports 24a, 24b are arranged on first main support 20a and a second main support 20b in a reversibly detachable manner.

FIG. 5 shows a first central support 26a of support skeleton 14 (see FIG. 1). First central support 26a has attachment points 22f, 22g. Attachment points 22f, 22g of first central support 26a are designed identical to attachment points 22d, 22e (see FIG. 3) of first edge support 24a. First central support 26a can, as a result, be arranged on main supports 20a, 20b (see FIG. 4) in a simple manner—just like first edge support 24a.

FIG. 6 shows a support skeleton 14 comprising multiple main supports 20a, 20b as well as edge supports 24a, 24b and central supports 26a-e arranged on main supports 20a, 20b in a reversibly detachable manner. Longitudinal axes 28a, 28b of main supports 20a, 20b run parallel to each other. Longitudinal axes 30a, 30b of edge supports 24a, 24b run offset and perpendicular to longitudinal axes 28a, 28b of main supports 20a, 20b. Furthermore, longitudinal axes 32a-e of central supports 26a-e run offset and parallel to longitudinal axes 28a, 28b of main supports 20a, 20b. As a result, support skeleton 14 forms receiving frame that can be expanded and reduced in size flexibly for multiple rectangular formwork elements 12a-c (see FIGS. 7 and 8).

FIG. 7 shows first formwork element 12a (see also FIG. 1). First formwork element 12a has a formwork element frame 34. Formwork element frame 34 preferably has at least one carrying aperture 36a-d. A formwork shell 38 is arranged on formwork element frame 34. Formwork element frame 34 is made from metal, in particular from steel or aluminum. To manufacture formwork element frame 34 in a simplified manner and easily repair damage to a corner of first formwork element 12a, first formwork element 12a has plastic cladding 42a-c on its corners 40a-d, only plastic cladding 42a-c of corners 40a-d being visible in FIG. 7 due to the perspective representation of first formwork element 12a.

FIG. 8 shows support skeleton 14 according to FIG. 6 with formwork elements 12a-c arranged thereon (see also FIG. 7). Formwork elements 12a-c are identical in design. In each case, two formwork elements 12a-c can be arranged between two central supports 26a-e or between an edge support 24a, 24b and the central support 26a, 26e nearest to edge support 24a, 24b. Formwork elements 12a-c can be mounted to support skeleton 14 and removed from support skeleton 14 independently of one another.

FIG. 9 shows support skeleton 14 according to FIG. 8 with all formwork elements 12a-1 that can be attached to support skeleton 14. Formwork elements 12a-1 can optionally be inserted between central supports 26a-e or between central supports 26a, 26e and edge supports 24a, 24b nearest to them. The locking of formwork elements 12a-1 is done

5

via end stops **44a-e** of central supports **26a-e** that are releasably screwed on, of which only the end stops **44a-e** arranged on central supports **26a-e** at one end are visible in FIG. 9 (see also FIG. 6 with respect to the end stops arranged at the other end). End stops **44a-e** are preferably plate-shaped.

FIG. 10 shows a ceiling formwork **46** comprising ceiling table **10**. According to the illustration in FIG. 10, further formwork elements **48a-c** can be added onto ceiling table **10**. Other formwork elements **48a-c** are connected to ceiling table **10** via support heads, only the support heads **50a, 50b** used for attachment to ceiling table **10** being visible in FIG. 10 due to the perspective representation. Support heads **50a, 50b** connect formwork elements **12g, 12k** to other formwork elements **48a, 48b**.

Formwork elements **12a-1** are identical in design to other formwork elements **48a-c**. Both formwork elements **12a-1** and other formwork elements **48a-c** have coupling points (see coupling points **56a-d** according to FIG. 11) for the connection of a support head **50a, 50b**. Support heads **50a, 50b** are arranged on formwork supports **52a, 52b**. Support heads **50a, 50b** form ceiling supports **54a, 54b** together with formwork supports **52a, 52b**.

FIG. 11 shows by way of example further formwork element **48c** to illustrate the flexible connectability of further formwork elements **48a-c** (see FIG. 10) to formwork elements **12a-1** (see FIG. 10). In FIG. 11, formwork shell **38** (see FIG. 7) is not visible. It can be seen from FIG. 11 that the further formwork element **48c** has coupling points **56a-d** in the area of its corners **40a-d**. As shown by way of example with reference to coupling point **56a**, coupling points **56a-d** preferably have locking projections **58a-c**. Coupling points **56a-d** provide the possibility of a corner connection of a support head **50c-f**. It can be seen from FIG. 11 that support heads **50c-f** can be mounted on further formwork element **48c** with various degrees of engagement such that respective support head **50c-f** can support different numbers of other formwork elements (not shown in FIG. 11).

Further formwork element **48c** has middle coupling points **60a, 60b** to make central support of further formwork element **48c** possible via support heads **50g, 50h**.

Support heads **50a-h** (see also FIG. 10) of ceiling formwork **46** (see FIG. 10) are preferably identical in design.

FIG. 12 shows a ceiling table **10**. Ceiling table **10** corresponds to ceiling table **10** according to FIG. 1. However, formwork element **12j** (see FIGS. 9 and 10) was not mounted. As a result of this, ceiling table **10** can be used at the construction site despite a concrete column **62**.

FIG. 13 shows a ceiling formwork **46** in which two ceiling tables **10** are fitted together according to FIG. 12 to frame concrete column **62**.

When viewing all figures of the drawing together, the invention relates, in summary, to a ceiling table **10** for the partial formwork of a concrete ceiling. Ceiling table **10** has at least one formwork element **12a-1**, in particular multiple formwork elements **12a-1**, that can be assembled on a lower frame **16** of ceiling table **10** in a nondestructive manner and can be disassembled from lower frame **16**. Ceiling table **10** has a support skeleton **14** on which at least one formwork element **12a-1**, in particular multiple formwork elements **12a-1**, is/are arranged. Support skeleton **14** can have multiple struts that can be connected together and separated from one another in a nondestructive manner. The support skeleton preferably has a pair of main supports **20a, 20b**, in particular parallel running main supports, on which a pair of edge supports **24a, 24b** and at least one central support **26a-e** that is arranged between the edge supports **24a, 24b** are

6

arranged. Edge supports **24a, 24b** and central support **26a-e** preferably run parallel to each other. The invention further relates to a ceiling formwork **46** comprising such a ceiling table **10**.

5 The invention claimed is:

1. A ceiling table of a ceiling formwork, the ceiling table comprising:

a lower frame comprising multiple supports;
a support skeleton that is attached to the lower frame, the support skeleton comprising a first main support and a first edge support, the first edge support being arranged on the first main support in a reversibly detachable manner, wherein the support skeleton has at least one central support that is arranged on the first main support in a reversibly detachable manner, a longitudinal axis of the at least one central support running parallel to a longitudinal axis of the first edge support; and
a plurality of formwork elements, the formwork elements each having a formwork element frame and a formwork shell arranged on the formwork element frame, at least a plurality of the plurality of formwork elements being attached to the support skeleton in a reversibly detachable manner, at least one formwork element of the plurality of formwork elements having a coupling point for arranging a support head of the ceiling formwork, wherein two formwork elements of the plurality of formwork elements are arranged between two central supports or between an edge support and the central support nearest to the edge support and can be mounted independently of one another on the support skeleton and can be removed from the support skeleton, wherein the formwork elements are selectively insertable between the central supports and the edge supports nearest to them, wherein the formwork elements are locked by releasably screwed-on end stops of the central supports.

2. The ceiling table according to claim 1, wherein all of the plurality of formwork elements are attached to the support skeleton in a reversibly detachable manner.

3. The ceiling table according to claim 1, wherein a longitudinal axis of the first main support runs perpendicular to a longitudinal axis of the first edge support.

4. The ceiling table according to claim 1, wherein the support skeleton has a second edge support that is attached to the first main support in a reversibly detachable manner.

5. The ceiling table according to claim 4, wherein a longitudinal axis of the second edge support runs parallel to a longitudinal axis of the first edge support.

6. The ceiling table according to claim 1, wherein the support skeleton has a second main support, a longitudinal axis of the second main support runs parallel to the first main support, the second main support being arranged on at least one of the first edge support or the second edge support in a reversibly detachable manner.

7. The ceiling table according to claim 1, wherein the lower frame has at least one roll at multiple supports.

8. The ceiling table according to claim 1, wherein at least one formwork element of the plurality of formwork elements has at least one plastic corner.

9. The ceiling table according to claim 1, wherein two formwork elements are of identical design each reversibly and detachably fastened to the support skeleton.

10. The ceiling table according to claim 1, wherein the releasably screwed-on end stops of the central beams each locking two locked formwork elements which are opposite each other with respect to the central beam on which the end stop is screwed.

11. A ceiling formwork comprising a ceiling table, the ceiling table comprising:
a lower frame comprising multiple supports;
a support skeleton that is attached to the lower frame, the support skeleton comprising a first main support and a first edge support, the first edge support being arranged on the first main support in a reversibly detachable manner, wherein the support skeleton has at least one central support that is arranged on the first main support in a reversibly detachable manner, a longitudinal axis of the at least one central support running parallel to a longitudinal axis of the first edge support;
a plurality of formwork elements, the formwork elements each having a formwork element frame and a formwork shell arranged on the formwork element frame, at least a plurality of the plurality of formwork elements being attached to the support skeleton in a reversibly detachable manner, at least one formwork element of the plurality of formwork elements having a coupling point for arranging a support head of the ceiling formwork,

5

10

15

wherein two formwork elements of the plurality of formwork elements are arranged between two central supports or between an edge support and the central support nearest to the edge support and can be mounted independently of one another on the support skeleton and can be removed from the support skeleton, wherein the formwork elements are selectively insertable between the central supports or between the central supports and the edge supports nearest to them, wherein the formwork elements are locked by releasably screwed-on end stops of the central supports;
a support head; and
a further formwork element, the support head being arranged on the further formwork element in a reversibly detachable manner and arranged on the ceiling table in a reversibly detachable manner.

12. The ceiling formwork according to claim 11, wherein the ceiling formwork has a ceiling support comprising the support head and a formwork support.
